[57] CLAIM

The ornamental design for a fishing lure, as shown and described.

DESCRIPTION

FIG. 1 is a perspective view of a first embodiment of a fishing lure showing my new design, the broken line showing of the fishing line and hook is for illustrative purposes only and forms no part of the claimed design. FIG. 2 is a side view of the fishing lure shown in FIG.

1;

FIG. 3 is a front view of the fishing lure shown in FIGS. 1 and 2;

FIG. 4 is a rear view of the fishing lure shown in FIG. 1; and

FIG. 5 is a side elevational view of a second embodiment of a fishing lure according to the present invention wherein a pair of identical rotors are mounted for rotation on a shaft between a cylindrical head piece and conical tail piece, with the rotor separated from each other by a spacer element.

FIG. 1

FIG. 3

FIG. 2

FIG. 4

FIG. 5
